United States Patent Office

Des. 221,178
Patented July 13, 1971

221,178

PLATE OR THE LIKE

Cynthia S. Gerow, Syracuse, N.Y., assignor to Corning
Glass Works, Corning, N.Y.

Filed May 12, 1970, Ser. No. 22,938

Term of patent 14 years

Int. Cl. D7—01

U.S. Cl. D44—15

The figure is a top plan view of a plate of conventional configuration showing my new design.

I claim:

The ornamental design for a plate or the like, as shown and described.
